United States Patent Office

Des. 201,120
Patented May 18, 1965

201,120

URINAL

E. Peter Robare, Louisville, Ky., assignor to American Radiator & Standard Sanitary Corporation, New York, N.Y., a corporation of Delaware

Filed Sept. 30, 1963, Ser. No. 76,809

Term of patent 14 years

(Cl. D4—5)

Fig. 1.

Fig. 5.

Fig. 4.

Fig. 2.

Fig. 3.

FIGURE 1 is a view, in top perspective, of a urinal showing my new design;

FIGURE 2 is a view in side elevation thereof;

FIGURE 3 is a plan view thereof;

FIGURE 4 is a front view thereof; and

FIGURE 5 is a bottom perspective view thereof.

I claim:

The ornamental design for a urinal, substantially as shown.
